VENETIAN BLIND CONTROL

Thora Magdalena Gertzon, New York, N. Y.

Application November 1, 1948, Serial No. 57,633

5 Claims. (Cl. 160—168)

1

This invention relates in general to a Venetian blind control and in particular to a control operated by a single cord. As far as I am aware, all Venetian blinds on the market are operated with four cords. Two lifting and lowering the blind and two for tilting the blades.

The principal object of my invention, is to provide a simple means of operating Venetian blinds.

Another object of my invention is to provide an improved type lock for locking the blind in any position without damage to the cord.

A still further object of my invention is to provide a system of rollers located in the support box at the top. Said rollers are to receive the two cords for lifting the blind, thus only one cord emerges from the support box. Said single cord is used for operating the blind.

A further object of my invention is to provide simple means of lifting, lowering and operating the blades with a single cord.

Further objects and advantages of my invention will appear from the following description in conjunction with attached drawing in which:

Fig. 1 is an elevation of the operating mechanism and the principal parts of my invention applied to a Venetian blind.

Fig. 2 is a transverse vertical elevation taken upon the line *a—a*, Fig. 1.

Fig. 3 is a diagram showing the arrangement of placing the two support cords into the support box.

Although my invention may be applied to any cover for doors and windows, regulating door and manhole cover openings, I will for the purpose of explanation describe the invention in connection with a Venetian blind of which the box 10 is the support of the Venetian blind, generally made of wood. 11 is a metal box embodying the principal parts of my invention. On Fig. 1, 11 is shown with the cover 12 removed. The wheels 13 are supported by their shafts going through the walls of box 11 and cover 12. The wheel 14 is supported by its shaft going through the carriage 15. The spring 16 in conjunction with the wheel 14 and the carriage 15 locks the cord 17 when it is so desired. A wedge-like member 18 is free to slide inside the carriage 15, operating plug 19 which controls 15 through the slot 20 which is part of 15. 21 and 22 are levers actuating a corrugated wheel 23 for tilting the blades through the blade support 24. 25 and 26 are pins riveted to 21 and 22 respectively. 27 is a spring washer holding tilt rail 24 at a desired angle. 28 is a fork sup-

2

porting 21, 22 and 23. 29 is a Venetian blind blade of which only one is shown. 30 is a canvas strip supporting the blades. 31 are screws attaching box 11 to 10. 32 are screws attaching cover 12 to box 11. 33 are cords lifting the blades 29 when the cord 17 is pulled down. 34 are wheels receiving cords 33. 35 are two double wheels receiving the two cords 33 when 17 is pulled down. 36 are guides preventing the cords 33 from twisting.

The operation of my invention is as follows:

On Fig. 1 cord 17 is held in a locked position through the force applied by spring 16. Pushing the cord 17 toward the right will move carriage 15 and the slide 18 to the right, releasing plug 19 into slot 20, thus keeping the wheel 14 also at the right, leaving cord 17 free to move either downwards by the force of the hand, lifting the Venetian blind up; or let 17 go upwards by the gravity force of the blind, thus the Venetian blind will go down. To stop it at any desired position, pull the cord 17 toward the left, thus 18 will push up plug 19 and the spring 16 will move the carriage 15 and the wheel 14 into the locked position. Pushing the cord 17 forward against the pin 25 will move the lever 21 against the wheel 2; turning 23 and 24, thus tilting the blades 29 clockwise facing line *a—a*.

I claim:

- 30 1. A Venetian blind control including an operating mechanism comprising a support box containing three pulleys, two of said pulleys journaled horizontally in said support box, a T-shaped carriage movably mounted in said box, a spring for actuating said carriage, one of said pulleys being journaled horizontally in said carriage, an operating cord passing through said pulleys, a bar movable inside said carriage, the position of said bar being controlled by the operating cord, a plunger movable in said box, said bar actuating said plunger vertically, said plunger controlling the relative position of said carriage by lateral movement of said bar by said operating cord.
- 35 2. A Venetian blind control including an operating mechanism comprising a support box, two pulleys journaled horizontally in said support box, a T-shaped carriage movably mounted in said support box, one pulley journaled horizontally in said carriage, an operating cord passing through said pulleys, said carriage being movable in one direction by said cord, a spring actuating said carriage in the opposite direction, 40 a bar movable laterally by said operating cord.
- 45 3. A Venetian blind control including an operating mechanism comprising a support box, two pulleys journaled horizontally in said support box, a T-shaped carriage movably mounted in said support box, one pulley journaled horizontally in said carriage, an operating cord passing through said pulleys, said carriage being movable in one direction by said cord, a spring actuating said carriage in the opposite direction, 50 a bar movable laterally by said operating cord.
- 55 4. A Venetian blind control including an operating mechanism comprising a support box, two pulleys journaled horizontally in said support box, a T-shaped carriage movably mounted in said support box, one pulley journaled horizontally in said carriage, an operating cord passing through said pulleys, said carriage being movable in one direction by said cord, a spring actuating said carriage in the opposite direction, a bar movable laterally by said operating cord.

a plunger actuated by said bar, said plunger controlling the relative position of said carriage, two pins, said operating cord extending downward between said two pins, a lever having arms, each of said pins being attached to a lever arm, a serrated wheel, said lever arms actuating said serrated wheel, turning said serrated wheel by forward or backward movement of said operating cord, a fork attached to said support box, said serrated wheel being horizontally journalled in said fork, a spring washer, said serrated wheel being held in a steady position by said spring washer.

3. A Venetian blind control including an operating mechanism comprising a support box, three pulleys, a T-shaped carriage, a spring, a plunger, a bar and an operating cord, two pins, said operating cord extending through said pulleys and extending downward between said two pins, lever arms, said pins being attached to said lever arms, a fork, a serrated wheel, said lever arms and said wheel being journalled in said fork, a spring washer tightening said serrated wheel, a shaft keyed to said serrated wheel extending laterally through said fork, said fork attached to said support box, said operating cord extended laterally into a distribution box comprising four horizontally journalled pulleys and seven guides guiding the lifting cords when the Venetian blind is opened, said distribution box containing all of said lifting cords when the Venetian blind is open, only said operating cord extending through said operating mechanism.

4. A Venetian blind control comprising a support box, two pulleys journalled horizontally in said support box, a T-shaped carriage, one said pulleys journalled horizontally in said carriage, a spring actuating said carriage, a bar inside said carriage, a plunger actuated by said bar, an operating cord extended through said pulleys and through said bar, two pins, said operating cord further extending between said two pins, two lever arms, said pins being attached to said lever arms, a spring washer for holding said wheel steady, a fork attached to said support box, said

serrated wheel and said lever arms being horizontally journalled therein, said operating cord extending into a distribution box having two pulleys and seven guides, the other end of said operating cord extending into said box, two lifting cords attached to said operating cord, said lifting cords supported by two pulleys in said distribution box.

5. A Venetian blind control comprising a support box, three pulleys, a spring, a T-shaped carriage, a plunger, a bar, two pins and an operating cord, said operating cord extending downward through said pulleys and between said pins, two of said pulleys being horizontally journalled in said support box and one of said pulleys horizontally journalled in said T-shaped carriage, a pipe attached to said support box for supporting said spring, said plunger actuated up and down by said bar, and said bar being actuated by lateral movement of said operating cord, lever arms, said operating cord actuating said lever arms through said pins, a serrated wheel, said lever arms turning said serrated wheel in either direction by forward or backward movement of said operating cord, a distribution box, cord pulleys and guides in said box, said operating cord extending into said distribution box through two pulleys and seven guides, lifting cords supported by two of said pulleys and attached to said operating cords, said distribution box containing all lifting cords 30 when the Venetian blind is open permitting only said operating cord to pass through said operating mechanism.

THORA MAGDALENA GERTZON.
